UNITED STATES PATENT OFFICE

LOUIS A. CAMEROTA, OF BURLINGTON, NEW JERSEY, ASSIGNOR TO WALTER WOOD, OF
PHILADELPHIA, PENNSYLVANIA

CHUCK FOR CENTRIFUGAL CASTING MACHINES

Application filed November 23, 1931. Serial No. 576,725.

My invention relates to centrifugal casting machines wherein cylindrical flasks are driven by a motor or other prime mover while molten metal is admitted to the flask for the casting of pipe or like articles, and more particularly the invention relates to a chuck used as the coupling member by which the driving shaft of the motor or prime mover is connected to the rotatable flask. The object of 10 my invention is to provide a chuck of this nature characterized by simplicity of manufacture, reliability of operation and adaptability to flasks of varying sizes.

Other objects and advantages characterizing my invention will become more fully apparent from the description hereinafter of one embodiment or example thereof, the description having reference to the accompanying drawing. Of the drawing:

20 Fig. I represents a side elevation of a centrifugal casting machine embodying a chuck of my invention.

Fig. II represents a cross-section of the same, taken as indicated by the lines II—II 25 of Fig. I.

Fig. III represents a perspective view of the chuck shown in Fig. I; and,

Fig. IV represents a perspective view of the chuck spacer shown in Fig. I.

30 In the drawing, there is shown a centrifugal casting machine comprising a prime mover in the form of a motor 1, a speed reducer 2, and a cylindrical pipe flask 3. The motor 1 and speed reducer 2 are mounted on a base plate 4 which in turn rests upon the foundry floor 5. The cylindrical pipe flask 3 is disposed in axial alignment with the driving shaft 6 and is mounted in bearings 7 having rollers 8 between which machined shoulders 9 of the flask are accommodated. To 35 admit the flask 3 to the centrifugal casting station, I employ skids 10 in the form of parallel rails from which the flasks may readily be moved onto the rollers 8.

40 A hood 11 surrounds the flask 3, and at one end of the hood there is shown a pouring spout 12 of conventional form. Opposite the pouring end the flask is formed with an annular flange 13 at the end thereof, the flange 50 being provided with a series of perforations

14. On the driving shaft 6 a chuck 15 is mounted and rigidly secured by means of a spacer 16, shown in detail in Fig. IV, and bolts 17. The chuck 15, as shown in Figs. II and III, is in the form of a flat plate having two oppositely directed arms 18 and 19. One such arm has bolted thereto a counterweight 20. The other such arm 19 is provided with a jaw 21 which is adjustable radially in a slot 22 and which may be secured at the desired radius from the axis of the driving shaft 6 by bolts 23.

The jaw 21 is in the form of a hook having its outer end projecting toward the driving shaft 6 and having its central portion 24 shaped to conform to the shape of the flange 13 on the flask 3. While fitting over the flange 13, the jaw 21 is not actually clamped to the flask with a locking connection. The jaw 21 engages a bolt 25 or like projection passing through a perforation 14 in the flanged end of the flask. Accordingly, when the motor is operated, rotary motion is transmitted from the driving shaft 6 through the chuck 15 and its jaw 21 to the bolt 25, and hence transmitted to the flask 3 which is in axial alignment with the driving shaft. The counterweight 20 serves to balance the arm 19 which carries the jaw 21 and hence prevents undue vibration.

With a chuck of the character described, it will be apparent that a flask 3 may be rolled into the centrifugal casting station, with the chuck turned to the position shown in Fig. I, in such manner that the flask is automatically engaged by the chuck without further work on the part of the operator. The flask 3 is restrained, by means of the shoulders 9 thereon which are accommodated between the pairs of rollers 8, against lateral movement, and it is maintained in alignment with the axis of the driving shaft by the position of the bearings which may be adjustable in vertical relation to the floor to take care of flasks of varying sizes.

From the above description it will be noted that the chuck of this invention is very inexpensive to manufacture and yet performs its intended function efficiently, and without requiring any labor on the part of the opera-

tor in connection with the coupling of the flask preparatory to its spinning movement, the flask being self-seating in the chuck. The removal of the flask from the machine is
5 accomplished with equal facility.

While I have described a particular form of chuck and a particular form of flanged end for a flask, it will be apparent that various changes may be made in the shape of
10 these parts without departing from the spirit of my invention as defined in the annexed claims.

Having thus described my invention, I claim:

15 1. In a centrifugal casting machine, including a prime mover having a driving shaft, and bearings for rotatably supporting a cylindrical flask in axial alignment with said driving shaft; a chuck for connecting
20 the driving shaft to an end of the flask, said chuck comprising an arm projecting radially from said driving shaft, and a jaw on said arm in the form of a hook having its end projecting toward said driving shaft, said
25 jaw being adapted to extend around the end of the flask and to engage a projection thereon to transmit rotary movement to the flask.

2. In a centrifugal casting machine, including a prime mover having a driving
30 shaft, a cylindrical flask having a flange at the end thereof, and bearings for rotatably supporting said flask in axial alignment with said driving shaft; a chuck for connecting the driving shaft to the flanged end of the
35 flask, said chuck comprising an arm projecting radially from said driving shaft, and a radially adjustable jaw on said arm in the form of a hook having its end projecting toward said driving shaft, said jaw being
40 adapted to extend around the flanged end of the flask and to engage a projection thereon to transmit rotary movement to the flask.

In testimony whereof, I have hereunto signed my name at Florence, New Jersey,
45 this 16th day of November, 1931.

LOUIS A. CAMEROTA.
